UNITED STATES PATENT OFFICE.

LAURITZ BREDEMBERG ANDESEN, OF MINNEAPOLIS, MINNESOTA, ASSIGNOR TO M. F. PATTERSON DENTAL SUPPLY CO., OF ST. PAUL, MINNESOTA, A CORPORATION OF ILLINOIS.

TOOL HANDLE.

Application filed November 12, 1923. Serial No. 674,277.

This invention relates to new and useful improvements in tool handles adapted for use to hold and support small tools such as dental drills and burrs and more particularly 5 relates to improvements in such handles as are commonly employed by dentists in the work of preparing teeth for dental repairs, such as fillings, inlays, bridges, etc., and also in the work of cleaning and polishing teeth. 10 To do this work different kinds of tools are employed, and it is therefore desirable that means be provided whereby such tools may easily and rapidly be changed without loss of time.

15 Dental tool handles of ordinary construction are usually provided with a rotatably mounted driven member or shaft having a clutch mechanism provided at the tool end thereof and adapted to clamp securely the 20 tool therein when in use. Rotary movement is transmitted to the driven member or shaft by means of a grooved pulley or other suitable means, secured to the upper end thereof, which is adapted to be operated by 25 the usual dental motor. When using such a tool handle, and especially when using such tools as a drill or burr, the driven shaft is often subjected to a considerable end thrust or load, which may be in either direction, de- 30 pending upon the action of the tool. Suitable thrust bearings are therefore provided adjacent the tool end of the handle, adapted to take up this load and thus permit the shaft to rotate freely without danger of 35 binding.

However, in using a tool handle such as the one above described, difficulty is often experienced in that fine particles of emery and pumice stone, mixed with saliva, work 40 around the rapidly revolving shank of the tool and into the bearing and clutch mechanism, thereby often causing serious damage thereto. To avoid the possibility of the bearing thus becoming unnecessarily worn 45 and damaged and also to maintain it in a sanitary condition, it is necessary that the bearing and associated parts be removed from the handle and thoroughly cleaned after usage in order that all grit and foreign 50 matter may be removed therefrom. This practically necessitates disassembling the tool handle, which is often inconvenient for the user, and therefore has a tendency to lead to neglect, with the subsequent ruina-

tion of the bearing in a comparatively short 55 time.

In the construction of the novel tool handle featured in this invention, means are provided for positively preventing any grit or foreign matter from entering the bearing when the handle is in use, thereby protecting the bearing and associated parts from unnecessary wear and damage and also eliminating the necessity of disassembling the handle each time it has been used. This 60 novel means is equally useful and effective whether the dental tool is in axial alignment with the handle or whether the tool is angularly operative such, for example, as the contra-angle, the right angle, etc. assemblies. 65

The handle is also provided with an improved clutch mechanism of simple and inexpensive construction, which may be quickly and easily actuated to grip or release the tool shank, by means of a finger 70 grip provided at the upper end of the handle.

The object of this invention, therefore is to provide an improved tool handle.

Other objects of the invention will more 80 fully appear from the following description and the accompanying drawings and will be pointed out in the annexed claims.

In the drawings, there has been disclosed a structure designed to carry out the various 85 objects of the invention, but it is to be understood that the invention is not confined to the exact features shown as various changes may be made within the scope of the claims which follow.

90 In the drawings:

Figure 1 is a longitudinal sectional view of my improved tool handle, showing the shank of a tool positioned between the jaws of the clutch, and also showing the means 95 provided at the tool end of the handle for preventing foreign matter from entering the bearing;

Figure 2 is a similar view, partially in side elevation, to show the clutch in open 100 position;

Figure 3 is a cross-sectional view on the line 3-3 of Figure 1;

Figure 4 is a partial sectional view of the lower or tool end of the handle with the tip 105 cap removed therefrom;

Figure 5 is a view showing the cap removed from the tool handle; and

Figure 6 is a perspective view of the packing washer removed from the cap.

In the selected embodiment of the invention here shown, for purposes of disclosure, 5 there is illustrated a dental tool handle comprising a cylindrical casing 11 preferably having a lower reduced end portion 12 upon which is mounted the usual outer shell 13, of any suitable non-conductive material, for 10 the purpose of providing a convenient hand-grip for the user.

The upper terminal end of the casing 11 is exteriorly threaded to receive a threaded head 14, having an upwardly extending integral boss 15 provided thereon. This boss 15 is concentric with the axis of the tool handle and functions to provide a bearing for the usual tool handle supporting arm 16, having 15 its other end connected to the usual supporting means, not shown. An annular groove or recess 17 is preferably provided in the boss 15 to receive the reduced end portion 20 of the screw 18. The usual fibre block 19 is also shown yieldably held against the periphery of the hub by means of the usual compression spring 21 and adjusting screw 22 and has the usual function of creating a slight friction in the bearing for the purpose 25 of retaining a good fit between the hub 15 and the bore of the arm 16, at the same time permitting the tool handle to be rotated relative to the supporting arm.

One of the important features of this 30 invention resides in the means provided at the upper end of the handle for taking up the axial load or thrust of the drive shaft, in either direction, instead of the usual thrust bearing usually provided for this purpose and mounted adjacent the lower or 35 tool end of the handle.

As shown in Figure 1, the upper portion 40 of the casing 11 is bored relatively large and is internally threaded to receive an adjusting nut 23, having the usual sockets 45 24 provided in the upper face thereof by means of which it may be relatively rotated within the casing to adjust its relative position therein. A set screw 25 is preferably provided to lock the nut 23 in adjusted 50 position. This nut functions to provide a seat for a suitable antifriction thrust bearing 26 mounted upon a hollow drive stem 27, the lower portion of which passes through the adjusting nut 23 and is terminally secured to the upper end of a relatively larger hollow drive shaft 28 by such means as the threads 29. An integral annular flange 31 is formed on the central portion 55 of the stem 27 adapted to have its lower face bearing against the upper face of the bearing 26. A similar thrust bearing 32 is mounted on the stem 27 above the flange 31 and an adjusting nut 33 is mounted on the upper portion of the stem 60 65 in abutting relation to the bearing 32. The

upper adjusting nut is likewise in threaded engagement with the upper inner threaded portion of the casing 11, so that the position of the drive stem 27 and bearings 26 and 32 may be relatively and properly adjusted 70 within the casing. The upper end of the nut 33 preferably extends above the upper end of the casing so that when the head 14 is screwed downwardly the inner face 34 thereof will bear against the nut and thus 75 lock it in adjusted position.

The two adjusting nuts 23 and 33 are preferably bored to provide a running fit for the stem 27, rotatably mounted therein. The stem 27 also preferably extends above 80 the upper face of the boss 15 and has the usual grooved drive pulley 35 fixedly mounted thereon. The lower face of the pulley 35 is preferably provided with a hub 36 which is counterbored to receive the projecting end of the boss 15 and to provide a running fit therefor. By thus partially 85 mounting the pulley upon the end of the stationary hub 15, the radial load of the shaft will be taken up by the hub and not 90 by the stem 27, which loosely passes through the boss 15, as shown.

As hereinbefore stated, the upper end of the hollow drive shaft 28 is terminally secured to the lower end of the drive stem 95 27, and downwardly extends therefrom substantially the entire length of the handle. The lower end of the shaft is preferably formed to provide a reduced end portion 37 adapted to receive a suitable bearing 100 sleeve 38 secured thereto. The lower or tool end of the reduced portion 12 of the casing 11 is terminally threaded to receive an end piece 39 which is suitably bored to provide a running fit for the sleeved end of the drive shaft 28. This end piece is 105 slightly conical in shape and is locked to the casing preferably by means of a headed screw 41, in threaded engagement with the wall of the end-piece 39. The reduced end portion 37 of the drive shaft is provided with an aperture 42 through which the tool shank may be inserted to the clutch mechanism.

Another important feature of this invention, 115 is the novel clutch mechanism provided for securing the tool to the handle while in use. Such means consists preferably in the provision of a pair of opposed clutch members 43 pivotally mounted upon a pivot pin 120 44 preferably having its ends secured to the drive shaft 28, as shown in Figures 3 and 4. These clutch members are positioned within an elongated opening 45 provided in the drive shaft 28 adjacent the lower end 125 thereof, and are provided with opposed clutch jaws 46 adapted to firmly grip the tool shank when inserted therein through the aperture 42. The upper end of each clutch member 43 is terminally provided with 130

with said shaft and adapted to clutch a tool shank, thrust bearings for said shaft mounted adjacent the drive end of said tool handle, adjusting members mounted upon said shaft and engaging said bearings and having a screw connection with said casing for taking up end play in the bearings, and whereby said shaft and associated parts may also be relatively moved in either axial direction to relatively adjust said shaft and clutch with relation to said casing.

5. A dental tool handle, comprising in combination a casing, a drive shaft rotatably mounted therein, a clutch associated with said shaft and adapted to clutch a tool shank, an annular flange provided upon said shaft adjacent the drive end of said handle, thrust bearings engaging said flange, and members adjustably secured to said casing 10 and engaging said thrust bearings whereby end play may be taken up and whereby said shaft may be relatively moved in either axial direction relative to said casing.

6. A dental tool handle, comprising in combination, a casing, a drive shaft therein, a clutch associated with said shaft and adapted to clutch a tool shank, an annular flange provided upon said shaft adjacent the drive end of said handle, thrust bearings 25 engaging said flange, an adjusting members mounted upon said shaft between said flange and said clutch and engaging one of said bearings, said member having a threaded engagement with said casing, an adjusting nut also mounted upon said shaft at the opposite side of said flange and engaging the other of said bearings, a portion of said ad-

justing nut extending beyond the end of said casing, and a cap received in threaded engagement with the exterior of said casing 40 adapted to engage said nut to lock it in adjusted position.

7. In a tool handle, the combination of a casing, a drive shaft rotatably borne in the casing, bearings therefor, a clutch associated with the shaft and adapted to clutch a tool shank, an annular flange on the shaft, bearing members on the shaft and engaged with said flange, and adjusting members mounted upon said shaft and engaged with said bearing members, said members being received in threaded engagement with said casing and adapted for axial movement to take up end play in said bearings and whereby the position of the clutch with relation to the casing may be maintained.

8. In a dental hand piece, the combination of a casing, a drive shaft rotatably borne in the casing and adapted to have a tool operatively connected thereto adjacent one end of the casing, an annular integral flange on the shaft, thrust bearings on the shaft and engaged with said flange, adjusting nuts secured to the casing and engaged with said bearings to take up end play of the shaft 65 in either direction, said bearings being all located within the casing relatively remote from the tool end thereof to protect the bearings from foreign matter entrant at the tool end of the casing.

In witness whereof, I have hereunto set my hand.

LAURITZ BREDEMBERG ANDRESEN.

inwardly extending rounded projections 47, between which a wedge 48 is inserted to spread the two members and thereby cause the jaws 46 to clutch the tool shank and thus 5 securely clamp it to the revolving shaft 28, as shown in Figure 1. It will be noted that the pivot pin 44 is preferably located adjacent the clutch jaws so that the hubs 49 of the clutch members may provide a stop 10 for the end of the tool shank, as shown, when inserted therein.

The upper portion of the wedge 48 is preferably cylindrical in form and fitted to the bore of the drive shaft. A clutch rod 15 51 is secured to the wedge 48 and upwardly extends therefrom through the hollow stem 27. A suitable finger grip 52 is secured to the upper end of the rod by means of which the wedge 48 may be partially withdrawn 20 from between the rounded projections 47 of the clutch members 43, to release the clutch. The body of the wedge is preferably of such length that the upper end thereof will terminally engage the lower end of the stem 27 25 before the point of the wedge has been completely withdrawn from between the clutch members, as shown in Figure 2. Thus, the wedge will always be in position to readily enter between the clutch members when it 30 is desired to clamp the tool shank.

Means are also provided for positively preventing any grit, such as fine particles of emery and pumice stone, from working up into the lower guide bearing or into the 35 clutch mechanism. Such means preferably consists in the provision of a tip cap 53 which is adapted to snugly fit over the casing end-piece 39 and is secured thereto in such manner that it may quickly and readily be 40 removed therefrom. A substantially T-shaped opening 54 is provided adjacent the upper edge thereof, adapted to receive the head of the screw 41 when the cap is positioned upon the casing tip, as shown in Figures 1 and 2. A slight rotation of the cap, after having been thus positioned will cause the head of the screw 41 to engage one end 45 of the opening 54, thereby locking the cap to the casing end-piece and therefore to the handle. A packing washer 55, (shown in Fig. 6) having an aperture 56 provided 50 therein, is removably mounted within the cap adjacent the terminal end thereof, adapted to be clamped against the bottom 55 face of the casing end-piece 39 and thereby positively prevent any foreign matter from entering the casing. This packing washer may readily be removed and replaced by a new one should it become worn or unsanitary 60 from use, by simply removing the cap 53 from the tool handle, as above described and as shown in Fig. 5.

From the foregoing description, therefore, it will readily be seen and understood that 65 by the removal of the usual thrust bearing

from the tool end of the handle and by mounting it adjacent the upper or drive end thereof, it will be practically impossible for any foreign matter to enter the bearing, thereby eliminating the usual cost of frequently having to renew such a bearing. A radial guide bearing is provided adjacent the tool end of the handle, and this bearing is protected against grit and foreign matter by means of the packing washer 55 and tip 70 cap 53. The clutch mechanism featured is also of very simple and inexpensive construction, comprising but few parts, and all such parts being practically indestructible. 75

Having thus described my invention, what so 80 I claim as new and desire to secure by Letters-Patent, is:

1. In a dental tool handle, the combination of a casing, having a removable end-piece at one end and a removable head at 85 the other end thereof, a radial bearing adjacent each end of the casing, a drive shaft mounted in the bearings and having a driving means at one end thereof, means for taking up end play of the drive shaft in 90 either direction, opposed clutch members pivotally mounted within the drive shaft, a clutch-actuating means slidably mounted within the drive shaft and having one end outwardly projecting through one end of 95 the tool handle to provide an operating means therefor, and a demountable end cap having a removable packing washer therein, fitted over the end of the casing end-piece to prevent dust and grit from entering the 100 casing.

2. In a dental tool handle, the combination of a casing having a demountable cap at the drive end thereof, a drive shaft mounted within the casing, a driving means secured to one end of the drive shaft, means adjacent the drive end of the casing for longitudinally adjusting the drive shaft and for taking up 105 end play thereof, a clutch mechanism mounted within the drive shaft, a clutch-actuating means slidably mounted within said shaft and operable from one end of the handle, a demountable cap having a removable packing 110 therein, mounted adjacent the tool end of the handle, and means at the drive end of the 115 handle for supporting said handle.

3. In a dental tool handle, the combination of a casing a flanged drive-shaft borne in the casing, tool-gripping means within the casing operatively connected to the shaft, 120 thrust bearings mounted on the shaft and engaged with the opposite sides of the flange on said shaft, and means engaged with the casing and operable to take up end play in said thrust bearings, while maintaining the 125 same relative position of said tool-gripping means to the casing.

4. A dental tool handle, comprising in combination, a casing, a drive shaft rotatably mounted therein, a clutch associated 130
